PLANE TABLE PAPER

Adolf W. Keuffel, Montclair, N. J., assignor to
 Keuffel & Esser Co., Hoboken, N. J., a corporation of New Jersey

Application November 3, 1932. Serial No. 641,033

8 Claims. (Cl. 45—131)

This invention relates broadly to drawing and more particularly to a drawing table and sheet material upon which a drawing is made, adapted for drawing table use.

5 The primary object of the present invention is the provision of a sheet material upon which drawings, sketches and the like may be made which will not change its dimensions under different atmospheric conditions and which may be 10 so secured that the securing devices do not interfere with the movement of instruments, such as T-squares and triangles, over the drawing surface.

The invention also seeks the combination of a drawing table and a drawing receiving material 15 such as paper or tracing cloth or the equivalent, the dimensions of which are unaffected by atmospheric conditions and which is adapted to be secured to the drawing table by fastening devices which shall not interfere with the movement of 20 drawing instruments.

In accordance with the invention, the material, upon the surface of which a drawing may be made, is provided with a reenforcement comprising a sheet-like material which will not change 25 its dimensions under different atmospheric conditions and in the preferred embodiment is a lamination of some metal interposed between paper or other laminations of fibrous material and so shaped that the reinforced lamination, at 30 least at predetermined areas, extends beyond that reenforcing lamination a sufficient distance to permit fastening devices to pass through the drawing receiving material into a drawing table without passing through the reenforcing lamination. 35 More particularly, a sheet of drawing paper, say, is secured, by suitable adhesive, to at least one side of a sheet of metal which is cut away at the corners and, conveniently, at predetermined points intermediate the corners, to permit the easy passage of securing means through 40 the paper into the plane table.

The surface of the drawing table may be depressed at a predetermined area or areas corresponding to the unreinforced or cut-out part or 45 parts of the metal backing of the drawing paper so that the heads of the thumb tacks or other securing devices which overlie the paper may be disposed in a plane beneath the surface of the paper upon which the drawing, in major part, is 50 made.

Within a depressed area, the drawing table may be provided with a wear resistant bushing, socket or the like adapted to removably receive a fastening device yieldingly threaded, or otherwise held 55 therein and having preferably a broad flat head

to overlie the sheet material upon which the drawing is made.

Preferably, sheets of fibrous material, such as 60 paper, are disposed upon both surfaces of a reinforcing sheet of some desirable metal which is cut away at predetermined areas, and the outer 65 layers of fibrous material are drawn together over the cut-out portions and caused to adhere, as by an adhesive, so that the strain on the outer layers is evenly distributed.

These and other objects of the invention and the means for their attainment will be more apparent from the following detailed description, taken in connection with the accompanying drawing, illustrating one embodiment by which 70 the invention may be realized, and in which:—

Figure 1 is a view showing, in plan, a drawing table or plane table to which a sheet of drawing paper is secured in accordance with this invention.

75 Figure 2 is an enlarged view, in plan, taken at one of the securing means for the paper, parts being broken away to show details of the paper.

Figure 3 is a vertical sectional view taken in the plane indicated by the line 3—3 of Figure 1, 80 looking in the direction of the arrows.

There is indicated, at 10, a drawing board or plane table hereinafter referred to, for convenience, as a plane table, for the reason that the invention will probably find its greatest usefulness in connection with plane tables, so-called, but by the term "plane table" is intended, broadly, any surface to which a sheet may be attached and a drawing made thereon. Predetermined areas 12 in the top of the plane table and proximate its four sides are recessed so that the paper may be depressed in these areas and the heads of securing devices may lie below the plane of the surface upon which the drawing or sketch is made. In the illustrated embodiment, the depressions are formed by cutting out a portion of the upper surface of the plane table, of gradually increasing depth to the lowest point at the center where the fastening device is located, the depression being, conveniently, a spherical segment in 90 shape and hence circular in plan.

The paper, in accordance with this invention, is so constructed as to retain its exact dimensions and neither increase or decrease in size nor warp under different climatic conditions. To this end, a reinforcing sheet of material, which is unaffected by atmospheric changes, for instance, a sheet of metal 14, as thin as may be found practical, is provided upon one surface with a sheet 16 105 of fibrous material, for instance, drawing paper, 110

tracing cloth or the like. For convenience in description, this sheet 16 will be referred to herein-after as drawing paper to cover broadly any type of sheet material suitable for the purpose. In 5 making the sheet of drawing paper, there is, preferably, first caused to adhere, upon each side of the reenforcing sheet, and by means of suitable adhesive, a sheet of fibrous material 18 capable of forming a bond both with the reenforcing sheet 10 14 and the drawing paper 16 on the upper side and a sheet 20 of fibrous material, such as paper, of suitable characteristic on the under side of the sheet. Of course, both sheets 16 and 20 may be alike, but since only one side of the laminated 15 sheet will usually be drawn upon, a less expensive sheet 20 can be used for the under side. The use of the bonding sheet is desirable although not necessary in all situations.

At areas of the drawing paper corresponding 20 to the aforesaid depressions 12 in the plane table, the reenforcing sheet 14 is cut away or cut back from the edge, as shown at 22, and the sheets of fibrous material 16, 18 and 20 are somewhat larger than the sheet of metal 14 so that, preferably, on all sides, the fibrous material is drawn 25 down over the edges of the reenforcing sheet including the edge of the cut-out portion 22 and joined together by suitable adhesive to form a laminated flexible sheet portion capable of permitting the passage therethrough of fastening 30 devices and equalizing the strain on the paper and also capable of being depressed into the depressions 12, so that the heads of fastening devices may lie wholly within the depression and not 35 obstruct the movement of drawing instruments thereover.

By gradually curving the surface of the depressions from the outer edge thereof to the fastening device, the laminated drawing paper is better 40 enabled to conform to the surface without being subjected to undue strain which might rupture the bond between the sheets.

While any character of fastening device, such 45 as thumb tacks, may be used to secure the laminated reenforced sheet to the plane table, there is shown, in the drawing, a screw and bushing fastening device which it is preferred to use with this invention. At substantially the center of each depression, there is formed a threaded hole 50 26 in the drawing board. This hole, conveniently, does not pass entirely through the drawing board. In this hole is received a threaded bushing or socket 28 of suitable material, preferably wear-resistant, such as brass, which is substantially 55 unaffected by changes in atmospheric conditions and the bore 30 therein is of somewhat increased diameter at its upper end 32 to facilitate the insertion of a screw-like co-operating fastening member. The fastening member has 60 a large flat head 34 beveled on the underside, as at 36, the head being provided with a screw threaded shank 38, which is split as at 40. The shank is passed through a hole 42 formed in the paper and is passed down into the threaded bore 65 30 of the bushing. The slot 40 in the shank gives a resiliency to the shank which causes it to expand to grip the bore 30 and yieldingly hold the same in place. The thickness of the head 34-36 is such that when the screw is turned 70 home in the bore, the top of the head will lie well below the top surface of the sheet 16, as clearly shown in Figure 3, thus offering no obstruction to the movement of drawing instruments, such as T-squares and the like, over the surface of the 75 paper in drawing thereon.

It will be obvious that any form of bushing or socket may be inserted in the board 10 within the area of the depression, it being merely necessary that the same be held in place and formed with means, for instance a hole, wholly or partly therethrough, to engage or receive the shank of a fastening device. Moreover the fastening device, while provided with a substantially flat head capable of overlying the drawing sheet at that point, may have a shank held in the hole either by a threaded connection or by resilient means. 80 85

While there has been shown one depression at each corner of the plane table 10 and one depression along each side intermediate the corners, it will be apparent that the number of fastening devices used will be dependent upon the size of the sheet to be affixed. Moreover, in some aspects of the invention plain thumb tacks or even clamps may be used to retain the paper against 90 displacement. 95

It will thus be seen that a laminated drawing paper reenforced with sheet metal has been provided particularly adapted for use with a plane table or other drawing board or table, and so constructed and arranged that the fastening devices will not mutilate the board or interfere with the free use of drawing instruments.

Various modifications will occur to those skilled in the art in the composition and configuration 105 of the plane table and the drawing paper as well as in the composition, configuration and disposition of the fastening devices, and no limitation is intended by the phraseology of the foregoing specification or illustrations in the accompanying drawing, except as indicated in the 110 appended claims.

What is claimed is:—

1. A plane table formed with a plurality of depressions in its upper surface proximate each 115 corner, in combination with drawing-paper comprising a reenforcement cut away to correspond with said depressions and fastening devices passing through the paper at the cut away portions and entering the depressed portions of the table. 120

2. In combination, a plane table and reenforced drawing-paper comprising a sheet of material unaffected by atmospheric changes, a sheet of fibrous material affixed to one surface of said sheet material, said first named sheet having 125 cut-out areas at predetermined points proximate its edges, said plane table being formed with a plurality of depressions in its upper surface corresponding to the cut-out area of said reenforcement and securing means for said drawing paper 130 adapted to engage said table within the areas of the depressions.

3. In combination, a plane table and reenforced drawing-paper comprising laminated sheet material, one sheet of which is unaffected by atmospheric changes, said last named sheet having cut-out areas at predetermined points proximate its edges, said plane table being formed with a plurality of depressions in its upper surface corresponding to the cut-out areas of the last named 140 sheet, and fastening devices for the drawing-paper in said depressions comprising a member formed with a hole and secured in the plane table within the area of the depressions, and paper retaining means having a head to overlie the paper 145 and a portion to be received in the hole.

4. In combination, a plane table and reenforced drawing-paper comprising sheet material unaffected by atmospheric changes and a sheet of fibrous material affixed to one surface of said 150

- sheet material, said first named sheet having cut-out areas at predetermined points proximate its edges, said plane table being formed with a plurality of depressions in its upper surface 5 corresponding to the cut-out areas of the reenforcement, the surfaces of said depressions curving gradually from the edge toward the center, and fastening devices comprising a bushing secured in the plane table at the center of each 10 depression and a large-headed screw the shank of which is split and adapted to be removably received in the bushing, the head of said screw being of a thickness such as to lie within the depression. 15
5. In combination, a plane table and reenforced laminated drawing paper comprising a sheet of material unaffected by atmospheric changes and a sheet of fibrous material affixed to at least one surface of said first named sheet, at least one 20 portion of said second named sheet projecting beyond the first named sheet and at least a corresponding portion of the surface of the plane table being depressed and adapted to receive securing means for the paper. 25
6. In combination, a plane table and reenforced laminated drawing paper comprising a sheet of material unaffected by atmospheric changes and 30
7. In combination, a drawing-paper adapted to retain its shape under varying atmospheric conditions comprising a sheet of material unaffected by atmospheric changes and having cut-out areas at predetermined points proximate its edges, a sheet of fibrous material affixed to both surfaces of said first named sheet material and extending over the cut-out areas and cause to adhere together. 80
8. In combination, a drawing-paper adapted to retain its shape under varying atmospheric conditions comprising a rectangular sheet of material unaffected by atmospheric changes and having cut-out areas at predetermined points proximate its edges, a rectangular sheet of fibrous material affixed to both surfaces of said first named sheet material and extending over the 85 cut-out areas and caused to adhere together. 90
9. In combination, a drawing-paper adapted to retain its shape under varying atmospheric conditions comprising a sheet of material unaffected by atmospheric changes and having cut-out areas at predetermined points proximate its edges, a sheet of fibrous material affixed to both surfaces of said first named sheet material and extending over the 95 cut-out areas and caused to adhere together. 100
